UNITED STATES PATENT OFFICE.

HIBBERT R. HOLMES, OF TORONTO, ONTARIO, CANADA.

DESIGN FOR A PNEUMATIC TIRE.

47,424.

Specification for Design.

Patented June 8, 1915.

Application filed April 9, 1914. Serial No. 830,816. Term of patent 3½ years.

To all whom it may concern:

Be it known that I, HIBBERT R. HOLMES, a subject of the King of Great Britain, residing at Toronto, in the county of York, in the Province of Ontario, in the Dominion of Canada, have invented a new, original, and ornamental Design for Pneumatic Tires, of which the following is a specification, reference being had to the accompanying drawing, forming part thereof.

The figure shows a perspective view of a portion or a section of a tire embodying the design.

I claim:

The ornamental design for a pneumatic tire as shown.

HIBBERT R. HOLMES.
